Robert W. Claiborne INVENTOR
BY
John W. Thompson his ATTORNEY

UNITED STATES PATENT OFFICE.

ROBERT W. CLAIBORNE, OF NEW CANAAN, CONNECTICUT.

MUSICAL INSTRUMENT.

Application filed May 28, 1927. Serial No. 194,877.

The present invention relates to an improvement in musical instruments, one object being to provide an inexpensive and simple instrument having the desirable musical qualities of a xylophone or marimba and yet so simple that it may readily be assembled by a child of ordinary intelligence. A further object has been to provide an instrument adapted for use in connection 10 with a plan of musical instruction for children which includes the actual making of instruments upon which they are taught to perform. In the case of a xylophone it will be a part of the course for the student to 15 make and match the parts constituting his particular instrument. Various types of xylophone are well known, some being simple but having only mediocre musical qualities, while others are more expensive and 20 complicated by the provision of resonance chambers and therefore not adapted to the requirements of student manufacture.

One form of instrument embodying my invention is illustrated in the drawings accompanying the present specification and in which

Figure 1 is a top plan view; and

Figure 2, a transverse section on the line 2—2 of Figure 1.

Referring to the drawings, a sound board 1 having its edges free to vibrate is mounted on a plurality of supporting members 2 which extend transversely across the underside of the sound board and have their outer 35 ends exposed adjacent to the lateral edges thereof. No other support for the sound board is provided or necessary. Bars 3 of wood or any other suitable material are mounted transversely across longitudinally 40 extending bar supporting blocks 4, the upper edges of which are preferably tapered to reduce the area of their supporting surface portions. The bars are retained in operative position by any suitable means such 45 as posts 5.

From the foregoing description taken in connection with the drawings, it will be apparent that the ends of the sound board extend considerably beyond the supporting 50 members 2 which are located at the nodal portions of said board. It will be understood that the location of the nodal points of different sound boards with respect to the ends thereof will vary with boards of different vibration affecting properties such

as length, breadth, thickness and character of the wood. In Figure 1 the supporting members 2 are shown as positioned at approximately the nodal points of a sound board of dried Cuban mahogany $\frac{5}{8}$ inches 60 thick, 10 inches wide and 30 inches long. A sufficiently exact determination of the location of the nodal points of any given sound board can be made by the well known experiment in which sand or dust is strewn on the 65 board, the latter being then vibrated as by drawing a violin bow across an edge thereof. Furthermore, there are no side or end walls or partitions underlying or engaging edge portions of the sound board so that the latter 70 is free to vibrate, and sound waves originating from vibrations thereof are unobstructed in their passage or movement therefrom. It has been found that this construction produces a full, rich musical note without the 75 use of complicated resonance chambers or of expensive or unusual materials of construction. The necessary parts may readily be made by a student and assembled in proper relation as part of his musical instruction. 80

I claim as my invention:

1. A musical instrument comprising a sound board having its peripheral edge portions free to vibrate, supporting means engaging the underside of said board at approximately the nodal points thereof, and sound producing means of predetermined tone characteristics mounted in operative relation with respect to said sound board. 85

2. A musical instrument comprising a sound board having its peripheral edge portions free to vibrate, supporting means engaging the underside of said board at approximately the nodal points thereof, spaced longitudinally extending bar supporting blocks secured to the upper side of said sound board and having their respective top or bar supporting faces narrower than their bottom or board engaging faces, and a plurality of sound producing bars mounted 90 on said blocks. 95

3. A musical instrument comprising a sound board having its peripheral edge portions free to vibrate, supporting means engaging the underside of said board at approximately the nodal points thereof, spaced longitudinally extending bar supporting blocks secured to the upper side of said sound board, a series of spaced posts 105 mounted in each block, the posts in one block 110

being in staggered relation to the posts in the other block, and a plurality of sound producing bars each having a single perforation adjacent to one end thereof, said bars being mounted on said blocks with the posts on one block engaging said perforations and with the unperforated end of each bar posi-

tioned between adjacent posts on the other block.

In testimony whereof, I have signed my name to this specification this 24th day of May, 1927.

ROBERT W. CLAIBORNE.
